UNITED STATES PATENT OFFICE.

ERNEST S. BOWEN, OF AUBURN, NEW YORK, ASSIGNOR OF ONE-HALF TO
WALTER L. FAY, OF SAME PLACE.

OIL-CUP.

SPECIFICATION forming part of Letters Patent No. 583,668, dated June 1, 1897.

Application filed November 19, 1896. Serial No. 612,707. (No model.)

To all whom it may concern:

Be it known that I, ERNEST S. BOWEN, a citizen of the United States, residing at Auburn, in the county of Cayuga and State of New York, have invented certain new and useful Improvements in Oil-Cups; and I do hereby declare the following to be a full, clear, and exact description of the invention, such as will enable others skilled in the art to which it appertains to make and use the same.

My invention is an improvement in oil-cups; and it consists in the novel features herein-after described, reference being had to the accompanying drawings, which illustrate two forms in which I have contemplated embodying my invention, and said invention is fully disclosed in the following description and claims.

Referring to the said drawings, Figure 1 represents an elevation of one form of oil-cup embodying my invention, showing the cap or cover raised. Fig. 2 is a vertical sectional view of the same. Fig. 3 is a similar sectional view showing the cap or cover in closed position. Figs. 4, 5, and 6 are views similar to Figs. 1, 2, and 3, illustrating another form of oil-cup embodying my invention, which is my preferred form.

In the drawings, Figs. 1, 2, and 3, A represents a cylindrical shell or casing provided on its exterior intermediate its ends with a laterally-extending flange a , polygonal in cross-section, as indicated in Fig. 1, so that it can be turned with a wrench. Below said flange the shell is provided with a screw-threaded portion a' , which screws into a suitable screw-threaded aperture in the part to which the oil-cup is applied.

B represents a cap or cover which fits snugly over the upper part of the shell A and extends down over it to the flange a , so as to cover all of the shell above the flange when the cap is in closed position, as shown in Fig. 3.

b represents a piston or plunger within the shell A, fitting snugly therein and having a stem b' extending through a guiding-aperture a^3 in the head a^2 of the shell, secured to the top of the cap B preferably by passing said stem through an aperture in the top of said

cap and riveting the stem, as shown in the drawings, but it may be secured in other ways.

C represents a coiled retracting-spring sur-

rounding the stem b' between the head a^2 of the shell and the piston b , so as to hold the cap B normally in its closed position. In this instance an oil-inlet aperture a^4 is provided in the side of the shell A just above the normal position of the piston b , as shown in Fig. 3.

The lower end of the shell or casing A is ordinarily provided with a discharge or delivery tube D, as shown, which is usually made of smaller bore than the shell and is of any desired length; but this tube may be omitted, if desired, as indicated in dotted lines in Fig. 3, in which case the lower end of the shell will simply be provided with a discharge-aperture.

The operation is as follows: To oil, the cap or cover B is lifted, thereby lifting both the cap and piston above the oil-inlet a^4 , so that the nozzle of an oil-can may be inserted and the oil introduced into the interior of the shell. It will be noted that the oil is discharged into a clear space within the shell and that there is nothing to impede its progress to the discharge aperture or tube. When the oil-can is removed and the cap released, the cap will be forced down by the spring C, which also forces down the piston b . As soon as the lower edge of the piston reaches the bottom of the oil-hole a^4 the further downward movement of the piston will exert a downward pressure upon the air between it and the oil and help to eject the oil through the discharge aperture or tube. It will also be noted that should the oil-cup be inverted, as it would be if attached to the hub of a revolving wheel or pulley, the oil would be prevented by the piston b from getting back to the oil-inlet a^4 and so leaking out of the cup.

It will also be seen that when the cap is in closed position no part of the device which has in any way come into contact with the oil or the nozzle of the oil-can is exposed, so that there will be no oily parts exposed to collect dust, and when the cap is raised the insertion of the nozzle of the oil-can into the inlet-aperture a^4 will not carry any dust or grit into the shell A and so into the bearing.

In Figs. 4, 5, and 6 I have shown what is my preferred form of oil-cup embodying my invention, the same being a slight modification of the form shown in Figs. 1, 2, and 3.

In these figures, E represents the shell or casting, which is provided with a flange e and screw-threaded portion e', exactly similar to the construction shown in Figs. 1, 2, and 3. 5 The part of the shell above the flange e is, however, greatly shortened and is provided with a head e², provided with a central aperture e³, as in the form first described. The lower end of the shell is shown provided with 10 a discharge-tube F, which may be dispensed with, if desired.

G represents the cap or cover, which is adapted to completely cover all of the shell above the flange e and to rest upon said flange 15 when in closed position.

g represents the piston, filling the interior of the shell E and provided with a hollow stem g', closed at its upper end, which extends up through the aperture e³ in the head e² of the 20 shell and is secured to the cap G in any desired manner, as by riveting, but it may be screwed into the head, if desired.

H represents a coiled retracting - spring which surrounds the stem g' between the piston 25 ton g and the head of the shell, as in the form first described, to hold the cap and piston in their lowest positions. In this form of my invention the oil-inlet aperture g³ is formed in the hollow stem g' instead of being in the 30 wall of the shell. When the cap is raised, the piston and stem g' will also be raised, thereby exposing the inlet-aperture g³ in the stem, through which the oil is introduced into the interior of the stem and so into the shell.

35 It will be seen that the oil has a free and uninterrupted passage from the inlet-aperture down through the stem and shell and through the discharge aperture or tube of the latter, and hence the oil can be forced in in large 40 quantities without backing up and flooding the exterior of the device, as is the case with many of the oil-cups now in use. When the cap is released and the oil-can removed, the spring H will draw down the cap and piston, 45 and as soon as the inlet-aperture g³ has passed into the shell E the further downward movement of the parts will cause a downward pressure upon the air between the oil and the piston and stem, thus aiding in expelling the

oil. It will be noted that this form of oil-cup 50 projects very slightly above the part to which the cup is secured, which makes it less conspicuous, less in the way, and less liable to injury. As in the form first described, so in this form the parts which come in contact 55 with the oil or oil-can are entirely covered when the cap is down, and there is no danger of the oil leaking out, even if the cup is inverted.

What I claim, and desire to secure by Letters Patent, is—

1. In an oil-cup the combination with the oil-receiving shell, of a movable cap inclosing the upper portion of said shell, a piston within said shell adapted to exert a downward pressure when moved downwardly, to force the oil from the shell, said shell being adapted to receive oil when the cover is raised, a stem connecting said piston and said cap and a retracting-spring interposed between the top of the shell and said piston for moving said cap and piston downwardly, substantially as described.

2. In an oil-cup the combination with the cylindrical shell, of a piston within the same, 75 a cap normally inclosing the upper portion of said shell, said shell being adapted to receive oil when the cap is raised, a stem connecting said cap and piston and extending through an aperture in the head of the shell, a retracting -spring encircling the stem, interposed between the piston and the head of the shell, substantially as described.

3. In an oil-cup the combination with the cylindrical shell, of a piston within the same, 85 a cap engaging the upper portion of said shell, a hollow stem connecting said piston and said cap, passing through an aperture in the head of said shell and provided with an inlet-opening, and a retracting-spring surrounding said 90 hollow stem between the piston and the head of the shell, substantially as described.

In testimony whereof I affix my signature in presence of two witnesses.

ERNEST S. BOWEN.
